[57] CLAIM

The ornamental design for an educational toy, as shown and described.

DESCRIPTION

FIG. 1 is a top plan view of an educational toy showing my new design;

FIG. 2 is a front elevational view thereof, the rear being a mirror image;

FIG. 3 is a bottom plan view thereof;

FIG. 4 is a left side elevational view thereof;

FIG. 5 is a right side elevational view thereof; and

FIG. 6 is a cross-sectional view thereof taken along the line 6—6 in FIG. 1.
